(57) **CLAIM**

The ornamental design for a multi-section wedge-shaped pile, as shown and described.

DESCRIPTION

FIG. 1 is a perspective view of a multi-section wedge-shaped pile in accordance with one embodiment of the present design;

FIG. 2 is one of a front view, a back view, a left side view, and a right side view of the multi-section wedge-shaped pile shown in FIG. 1;

FIG. 3 is a top view or a bottom view of the multi-section wedge-shaped pile shown in FIG. 1;

FIG. 4 is a perspective view of another multi-section wedge-shaped pile in accordance with another embodiment of the present design;

FIG. 5 is one of a front view, a back view, a left side view, and a right side view of the multi-section wedge-shaped pile shown in FIG. 4;

FIG. 6 is a top view or a bottom view of the multi-section wedge-shaped pile shown in FIG. 4; and,

FIG. 7 is a perspective view of the multi-section wedge-shaped pile shown in FIG. 4 when in use in accordance with the present invention.

1 Claim, 5 Drawing Sheets
